UNITED STATES PATENT OFFICE.

DONALD G. LITTLE, OF EDGEWOOD, PENNSYLVANIA, ASSIGNOR TO WESTINGHOUSE ELECTRIC & MANUFACTURING COMPANY, A CORPORATION OF PENNSYLVANIA.

VACUUM-TUBE STABILIZING MEANS.

Application filed March 1, 1922. Serial No. 540,326.

To all whom it may concern:

Be it known that I, DONALD G. LITTLE, a citizen of the United States, and a resident of Edgewood, in the county of Allegheny and State of Pennsylvania, have invented a new and useful Improvement in Vacuum-Tube Stabilizing Means, of which the following is a specification.

My invention relates to wireless telegraphy and particularly to high-power wireless transmission systems employing vacuum tubes as modulators.

An important object of my invention is to provide a high-power wireless transmission system embodying a modulating system of such design as to admit of the utilization of parallel-connected modulating tubes having dissimilar characteristics.

It is generally known that vacuum tubes, when employed in parallel relation as modulators or as amplifiers, should have straight-line characteristic curves of similar slopes at predetermined operating voltage, otherwise unstable operation ensues. In practice, however, it is extremely difficult to manufacture tubes having such operating characteristics, especially for power outputs of 250 watts and more.

According to my invention, I provide a modulating system wherein the power supplied to an oscillation generator system is modulated by a pair of parallel-associated modulator tubes having dissimilar characteristics. The desired stabilizing result is obtained by including adjustable resistors in the leads to the modulator-tube plates.

With these and other objects and applications in view, my invention further consists in the nature, the mode of operation and the constructional details hereinafter described and claimed and illustrated in the accompanying drawing, wherein:

The single figure is a diagrammatic view of a wireless transmission system embodying my invention.

In the drawing, a well known type of vacuum-tube oscillation-generator system 1 is shown as operatively associated with an antenna circuit 2 and with a constant source of direct-current energy 3 and a modulating system 4. The oscillation generator system comprises a three-electrode tube 5 having an anode 6, a grid 7 and a hot cathode 8 suitably disposed therein, the latter being energized

from a direct-current source of energy 9 through a resistor 11.

A grid-filament circuit for the tube 5 comprises a biasing condenser 12, a grid leak 13 connected in shunt thereto and a portion 14 of a tuning coil 15 which is serially included in the antenna circuit 2. A plate-filament circuit includes a condenser 16 of low impedance to currents of radio frequency and a portion 17 of the tuning coil 15. The antenna circuit 2, in addition to the tuning coil 15 includes an antenna 18, a tuning coil 19 and a ground conductor 21.

The constant source of direct-current energy 3 comprises a direct-current generator 22 and a series-connected reactor 23. Opposite terminals 24 and 25 of said source of energy 3 are connected by conductors 26 and 27, respectively, to the plate 6 and to the filament 8 of said vacuum tube 5. A radio-frequency choke coil 28 may be included in the conductor 26 to prevent the dissipation of the radio-frequency energy.

A pair of modulator tubes 29 and 31, comprising plate elements 32 and 33, grid elements 34 and 35, and hot cathode elements 36 and 37 have their plate and filament elements connected to the opposite terminals 24 and 25 of the source of energy 3 by means of conductors 38 and 39, respectively. The hot cathodes 36 and 37 may be energized from a common source of direct-current energy 41 through resistors 42 and 43, respectively.

Adjustable resistors 44 and 45 are interposed between the connections of the anodes 32 and 33, respectively, to conductor 38. In actual practice, I have found that, when employing modulator tubes having impedances of approximately 13,000 ohms, the resistance of the resistors 44 and 45 should be of the order of 5,000 ohms.

A conductor 46 serves to connect the grid elements 34 and 35 and the hot-cathode elements 36 and 37 in parallel relation to a biasing source of energy 47 and a secondary winding 48 of a coupling transformer 49. An amplifier tube 52 comprises an anode 53, a grid electrode 54 and a hot cathode 55, the latter being energized from a direct-current source of energy 56 through a resistor 57. A conductor 58 serves to connect the anode 53 to the positive terminal of the direct-current generator 22 through a primary winding 59 of the transformer 49 and an

adjustable resistor 61, the amplifying effect of the tube 52 being determined by means of said resistor 61.

The hot cathode 55 is connected, by a conductor 62, to a negative terminal 25 of the direct-current generator 22. A grid-filament circuit for the amplifier tube 52 includes a biasing source of energy 63 and a secondary winding 64 of a modulating transformer 65, the primary winding 66 of which is included in a circuit which may also contain a direct-current source of energy 67 and a microphone transmitter 68.

The resistors 44 and 45 are adjusted to such value as to cause the characteristic curves of the modulator tubes 29 and 31 to have similar slopes at the optimum operating voltage, thus eliminating the tendency for one tube to take the whole load.

Upon speaking into the microphone transmitter 68, variable potentials are subsequently impressed upon the grid elements 34 and 35 of the modulator tubes 29 and 31, thereby correspondingly modulating the impedances thereof and hence the resulting power supply to the oscillation generator system 1.

While I have shown a specific embodiment of my invention, for the purpose of describing the same and illustrating its principles of operation, it is apparent that various changes and modifications may be made therein without departing from the spirit of my invention. I desire, therefore, that only such limitations shall be imposed thereon as are specifically set forth in the appended claims or demanded by the prior art.

I claim as my invention:

1. In a radio sending device, a generator and a modulator operatively associated therewith, said modulator including a plurality of tube devices in parallel and means for separately adjusting the plate potential of each of said tube devices.

2. In a radio sending device, a source of energy, a vacuum tube oscillation generator energized therefrom and a modulator diverting varying amounts of energy from said generator, said modulator including a plurality of tubes, each having a plate circuit, said plate circuits being in parallel and individually adjustable impedances, one in each of said plate circuits.

3. In a radio sending device, a source of energy, a vacuum tube oscillation generator energized therefrom and a modulator diverting varying amounts of energy from said generator, said modulator including a plurality of three-electrode vacuum tubes having their cathodes connected together, their grids connected together and connections from their anodes to a common point, said last named connections including individually adjustable resistances, one for the anode of each of said vacuum tubes.

4. In a radio sending device, a source of energy, a vacuum tube oscillation generator energized therefrom and a modulator diverting varying amounts of energy from said generator, said modulator including a plurality of three-electrode vacuum tubes having their cathodes connected together, and their grids connected together, a signal controlled device controlling all of said grids simultaneously, and means including a common connection and a plurality of separately adjustable resistances, one for each of said tubes, for individually adjusting the plate voltage of each tube, whereby the tubes may be given characteristics sufficiently alike to enable said tubes to work together in parallel for modulating the output of said generator in accordance with the signals.

In testimony whereof, I have hereunto subscribed my name this 25th day of February 1922.

DONALD G. LITTLE.
